UNITED STATES PATENT OFFICE.

CHARLES H. NORTON, OF WORCESTER, MASSACHUSETTS, ASSIGNOR TO THE NORTON GRINDING CO., OF WORCESTER, MASSACHUSETTS, A CORPORATION OF MASSACHUSETTS.

GRINDING-MACHINE.

No. 869,194.

Specification of Letters Patent.

Patented Oct. 22, 1907.

Application filed October 9, 1906. Serial No. 338,159.

To all whom it may concern:

Be it known that I, CHARLES H. NORTON, a citizen of the United States, residing at Worcester, in the county of Worcester and State of Massachusetts, have 5 invented a new and useful Grinding-Machine, of which the following is a specification.

My invention relates to a machine for grinding car-wheels and similar objects which can be rotated on an axis while the grinding wheels are rotated in contact 10 with the surface thereof.

The principal objects of my invention are to provide adjustable supports for the car-wheel axle; provide for accurately positioning the wheel and axle with respect to mechanism for rotating the same; provide an improved floating drive for the axle; improve the means for adjusting the position of the grinding wheels in all directions, provide convenient and effective means for automatically feeding the grinding wheels across the faces of the car wheels, provide for automatically stopping the traverse of the grinding wheels or of either of them at any desired time at the limit of their traverse and prevent their being stopped at any other point; provide for locating the various parts required in the operation of grinding car wheels and the like in convenient relations with respect to each other; and generally improve the construction and operation of machines of this character so as to simplify the same and increase their efficiency, and so as to operate all the mechanism from a single source of power.

Reference is to be had to the accompanying drawings, in which

Figure 1 is a front elevation of a machine illustrating my invention, parts being broken away to show elements in the rear. Fig. 2 is a plan of the same with the 35 over-head driving mechanism removed. Fig. 3 is a plan of one of the grinding-wheel-supports and the traverse mechanism for a grinding wheel on an enlarged scale. Fig. 4 is a plan of the work-drive mechanism. Fig. 5 is a transverse sectional view of a pillow block for 40 supporting the car-wheel-shaft. Fig. 6 is a central longitudinal section of the pillow-block. Fig. 7 is a longitudinal vertical section of one of the thrust bearings. Fig. 8 is a front elevation of the work-drive-stand. Fig. 9 is a section on the line 9—9 of Fig. 4, showing an 45 end elevation of the work-drive-stand and the driving mechanism. Fig. 10 is a face view of an equalizing plate employed on the work-drive-stand. Fig. 11 is a rear elevation of one of the grinding-wheel slides and wheel traverse mechanism. Fig. 12 is a plan of a portion 50 of the wheel traverse mechanism. Fig. 13 is a plan showing the wheel traverse eccentric. Fig. 14 is an end elevation of a slide-stop striker. Fig. 15 is a side elevation of one of the grinding-wheel slides. Fig.

16 is a plan of the base for said slide, and Fig. 17 is a section of the same on the line 17—17 of Fig. 16.

55

Although the invention may be carried out in a machine constructed to grind only one car wheel or other cylindrical or conical surface as a safe door, for example, I have provided convenient means whereby it may be applied in such a manner as to simultaneously 60 grind off two conical car-wheels on an axle and the above described drawings illustrate the invention as applied in this manner.

For the purpose of driving all parts of the machine from a single source of power, I have mounted on a 65 base 10 a pair of uprights 11—11 which support hangers for a counter shaft 12. This counter-shaft may be driven from a motor 13 or other source of power, and it is provided with a series of pulleys or other power transmitting devices for driving the various parts of the 70 machine. For driving the work I have shown this shaft as provided with a cone-pulley 14 operating a cone-pulley 15 shown in Figs. 2 and 4. On the shaft which carries the latter pulley is a bevel pinion 16 driving a bevel gear 17 which is loosely mounted on a shaft 75 18. The gear 17 is provided with a clutch section 19, and on the shaft 18 is mounted a sliding clutch member 20 which is manipulated by a rod 21 and a starting lever 22. When the clutch is thrown into connection with the clutch section 19 the rotation of the pulley 15 is 80 transmitted to the shaft 18, and from that through a worm 23 to a worm-wheel 24. This worm-wheel is in a bearing 25 on a work-drive-stand 26 mounted on the base 10, and it is designed to rotate the work which is 85 shown in the present case in the form of a pair of car-wheels A fixed on an axle B which is shown as projecting beyond the outer sides of the wheels and rests in bearings which will be described below.

In order to permit conveniently placing the axle in position, the bearing 25 is provided as usual with an 90 opening 27 in the top thereof to permit the shaft B to be deposited in it. In order to permit the shaft to be lowered in this manner the worm-wheel is provided with a removable segment 28. This segment has shoulders 29 fitting corresponding shoulders on the worm-wheel, and is provided with a yoke 30 which is forced against a surface 31 on the worm-wheel by any desired means in order to clamp the segment and yoke in position. The means which I have shown for clamping these parts is in the form of a bolt 32 projecting from the segment 28 and a nut on the bolt and on the inside of the yoke. The worm wheel is provided with an open center to accommodate the shaft B.

In order to obviate any inequality in the centering of the shaft in the worm-wheel 24, the latter is provided with an equalizing plate 33 shown in detail in 105

Fig. 10. This plate is of a general horse-shoe shape to permit the shaft to be lowered to the center of the worm-wheel, and it is provided with a pair of opposite radial ways 34 for receiving grooves on the worm-wheel. It also has grooves 35 on its opposite face, preferably located at substantially right angles to the ways 34, and receiving ways on a work-drive-dog 36 which is of a shape similar to that of the equalizing plate. The plate 33 has gibs 36 for assisting in holding the dog. Adjusting screws 37 are carried by the work-drive-dog for engaging the shaft and rotating the same. The equalizing plate does not positively support the work-drive-dog in all positions, but constitutes a floating drive for the axle B, being movable to accommodate any inequalities in the centering of the latter.

The parts so far described provide for rotating the axle carrying the car-wheels, but do not provide for supporting it. For this purpose a pair of pillow-blocks 38 are employed. These pillow-blocks are mounted to slide toward and from each other along ways 39 so that they can accommodate axles in which the bearings are either inside or outside the wheels. For the purpose of adjusting these pillow-blocks they are provided with an adjusting right and left-hand screw 40, and a ratchet wrench 41 is used to engage a ratchet wheel 42 fixed to the screw for the purpose of rotating it. This screw has bearings in the stationary work-drive-stand 26 and passes into screw-threaded openings in the pillow-blocks 38.

In order to provide for conveniently supporting the car axle on the pillow-blocks each is provided with a spherical bearing 43 which is free to turn in all directions but one, being kept from turning circumferentially with respect to the axle by means of a pin 44 engaging a longitudinal groove in the bottom of the bearing. By using this automatic adjustment it is not necessary to be so particular about lining up the bearings, and there is no danger of binding.

When an axle is a little small it will rest on the bottom of a cylindrical bearing and be free to vibrate therein. Consequently in this class of work such a bearing will not provide means for connecting the rotating work with the base of the machine and affording a positive non-vibrating support therefor. In order to avoid this, I have provided means whereby the axle will always bear at two points even if it is materially smaller than the standard bearing in the pillow block. To accomplish this these bearings are cut out along the bottom of their bearing surfaces, and the space filled with a strip of soft yielding material 45, as felt, extending from one end of the bearing to the other and saturated with oil. Thus the axle always will have at least two bearing points and the felt affords self lubrication.

For the purpose of preventing end play, thrust bearings are employed. To make these bearings more readily adjustable, and especially to provide for efficient operation when the center bore in the axle is not in center with the bearing surface and to otherwise improve them, I have shown them as constructed in the following manner. They are provided with slots 46 through which clamping screws pass to secure them on a projection of the pillow block. The projection has two sets of holes 47 for the screws so that the bearings may be placed in proper position for axles with either outside or inside bearings. The bearings are included in cas-

ings 48 one of which is provided with a sliding-spindle 49. At its bearing end this spindle has a disk 50 on which bears a ball 51 held in position by a ball-retainer 52 and a washer 53. The ball and ball retainer are considerably smaller than the cavities in which they are located so as to have vertical and lateral play to accommodate axles, the center bores of which have got out of center. The washer is for holding them on the casing. The spindle 49 is preferably hollow, and is provided with a screw threaded opening into which an adjusting end-thrust screw 54 is adapted to enter. This screw has a bearing 55 on the casing and hand-wheel 56 for operating it. A binding screw 57 is employed for engaging the spindle and holding it in adjusted positions and also for preventing the rotation of the spindle.

In order to properly grind the conical surfaces of the two car wheels, a pair of grinding wheels 58 are employed. These wheels are provided with shields 58^a if desired and are operated from the counter-shaft 12 by means of a pair of pulleys 59—59 thereon. Binders 59^a 85 are shown to permit them to deliver power to cone pulleys 60 on the shafts on which the grinding-wheels are mounted. Each of these shafts is located in bearings on a main slide 61 which is adjustable on an intermediate slide 62 by means of a hand-wheel 63 connected with 90 an adjusting screw by means of gearing 64. The intermediate slide is adjustable along a slide-base 65 by means of a hand-wheel 66 connected with a gear 67 mounted on a threaded nut 68, through which passes a non-rotating screw 69. By rotating the hand-wheel 66 95 the intermediate slide is moved longitudinally with respect to the non-rotatable screw 69. The slide-base 65 is swiveled on the main base 10 of the machine, clamping bolts 70, passing through curved slots 71, being employed for holding the base in adjusted positions. The movement of the intermediate slide across the slide base is very short and necessarily slow. Consequently the ways on which it slides are liable to get gummed up in practice. To avoid this, I have inclosed a laterally grooved guide way 72 in a receptacle 73 for 105 oil. On the other side of the slide-base a flat grooved bearing surface 74 is provided which is also inclosed in a receptacle 75 for oil. It will be seen, therefore, that the intermediate slide moves constantly in a bath of oil. The slide has overhanging lips 75^a for protecting 110 the bearing surfaces from dust and the like.

The mechanism described above provides for adjusting the main slide and grinding wheel in both directions. I have also provided means for causing the grinding wheel to reciprocate across the surface of the car-wheel from the flange to the edge so as to grind the same in an efficient manner. For this purpose the counter-shaft 12 is provided with a cone-pulley 80 or the like, delivering power to a cone pulley 81 mounted on a wheel traverse speed stand 82. This pulley transmits power through gears 83 and 84 to a shaft 85. This shaft is connected by a pair of clutches 86 with a pair of shafts 87, one located at each end thereof. Each of these shafts transmits power by means of a worm 88 and a worm-wheel 89 to a traverse wheel eccentric 90. On 120 each of these eccentrics is a connecting rod 91 which is pivotally connected with one of the screws 69 which, as has before been stated, is connected with the nut 68. The rotation of the shafts 87 therefore transmits to the intermediate slide a reciprocating motion, and as these 130

slides are adjusted in angular position by the swiveling of the slide-bases the grinding wheels are given such a traverse that they will grind off a cylindrical or conical surface as may be desired.

- 5 The movable members of the clutches 86 are operated in any desired manner so as to enable the operator to close them at will, but to prevent him from opening them except at the end of the traverse of the wheels. This is accomplished in the form illustrated by forks 10, 92, each connected with a sliding shaft 93, operated by a starting lever 94. A spring 95 is provided for normally forcing the shaft into such a position as to open the clutch and prevent transmission of power from the shaft 85 to the shafts 87. When the starting lever is 15 turned to bring the clutch sections into engagement, a catch 96 on the shaft 93 slips beyond a projection on a gravity pawl 97, and the latter drops so that the projection falls behind the catch and prevents the opening of the clutch.
- 20 For the purpose of automatically releasing the pawl 97 to permit the spring 95 to open the clutch I have provided the following mechanism. On a bracket 98 mounted at one end of the screw 69 is pivotally supported a slide-stop striker 99 having a handle by which 25 it may be manipulated. This striker is pivoted on the bracket in such a manner that when in the position shown in full lines in Fig. 14, the heavier end of the striker will be on the opposite side of the pivot from the end of the bracket against which the other end of the 30 striker engages, so that the striker will remain in this position. When tipped over to the position shown in dotted lines, gravity will hold it in that position. In the latter position the end of the striker is so located that on the reciprocation of the screw 69, the striker 35 will engage an adjustable screw 100 mounted on a sliding stop pawl lifter 101. This lifter is provided with an arm 102 having a slanting surface engaging under a complementary surface of the pawl 97 to lift the latter on the rearward reciprocation of the screw 69 and slide- 40 stop striker. This permits the spring 95 to force the clutch sections apart. These parts are, of course, duplicated on the two sides of the machine, and the mechanism ordinarily will operate until one of the strikers 99 is tipped over in the position shown in dotted lines 45 in Fig. 14. Then on the next stroke of the eccentric 90 when the latter is at the limit of its stroke in the position shown in Fig. 12, the striker will engage the screw 100 and disconnect the shaft 85 from its driving mechanism. Therefore, either of the grinding wheels 50 can be thrown out of operation independently of the other.

It will be seen that the means for causing the traverse of the wheels is connected with the means for adjusting the same and is operable in all adjusted positions of the 55 slide on which the grinding wheel is supported.

For the purpose of conveniently supplying water for the grinding operation the counter-shaft 12 is provided with a pulley 103 for driving a pump 104. This pump conveys water from a tank 105 conveniently located, 60 through pipes 106 to nozzles 107 located in proper position over the wheels.

It will be seen that by the employment of the principles herein illustrated, whether in the form shown or otherwise, within the scope of my invention, most convenient and efficient means is provided for positioning

the car-wheels or other articles to be worked, rotating the same, adjusting the pillow-blocks to provide for inside and outside bearings, etc., adjusting the grinding wheels in all necessary ways, causing the grinding wheels to traverse in a most efficient and simple manner, automatically stopping either or both of the grinding-wheels at the convenience of the operator, preventing the operator stopping them at an intermediate point of their traverse, supplying water to the grinding-wheels, and performing all the other operations which are desirable in this class of work, all from the same source of power.

While I have illustrated and described herein an improved form of bearing and an adjustable end-thrust bearing, I do not herein claim the same, as they constitute a separate invention on which I reserve the right to file a divisional application or applications.

While I have illustrated and described a particular form in which my invention may be embodied, I am aware that many modifications may be made therein by any person skilled in the art without departing from the scope of the invention as expressed in the claims. Therefore, I do not wish to be limited to the particular elements of construction shown, but

What I do claim and desire to secure by Letters Patent is:—

1. In a grinding machine, the combination of a movable grinding wheel support, rotatable means for adjusting the support, and means connected with and acting through the adjusting means for reciprocating the support. 95
2. In a grinding machine, the combination of a movable grinding wheel support, rotatable means for adjusting the support, and means connected with the adjusting means for reciprocating the support in the direction in which the support is adjusted. 100
3. In a grinding machine, the combination of a movable grinding wheel support, an adjusting screw connected therewith, means on the support for engaging the adjusting screw, said means and screw being relatively rotatable, whereby the operation of said means will adjust the support, and means for reciprocating the adjusting screw. 105
4. In a grinding machine, the combination of a grinding wheel support, a non-rotatable screw, an adjusting nut for the screw rotatably mounted on said support, rotatable means for operating the nut and adjusting it on said screw and means for longitudinally reciprocating the screw. 110
5. In a grinding machine, the combination of a movable grinding wheel support, a screw, a nut on said screw mounted to move with said support, a hand-wheel, means for connecting the hand-wheel to produce a relative rotation between said screw and nut to adjust the same with respect to each other, and means for longitudinally reciprocating the screw. 115
6. In a grinding machine, the combination of a movable grinding wheel support, a non-rotatable screw, a nut for said screw rotatably mounted on said support, gearing connected with said nut, a hand-wheel for operating said gearing and adjusting the nut, and means for longitudinally reciprocating the screw. 120
7. In a grinding machine, the combination of a grinding wheel support, a non-rotatable screw, an adjusting nut for said screw mounted on the support, operating means for adjusting the nut, and mechanism for longitudinally reciprocating the screw. 125
8. In a grinding machine, the combination of a grinding wheel support, a non-rotatable screw, an adjusting nut for said screw mounted on the support, operating means for adjusting the nut, and mechanism for longitudinally reciprocating the screw, said mechanism comprising an eccentric and a connecting rod connected with the screw and operated by the eccentric. 130
9. In a grinding machine, the combination of a movable grinding wheel support, a nut rotatably mounted thereon, a non-rotatable screw engaging said nut, a connecting

- rod connected with said screw, and an eccentric for operating said connecting rod.
10. In a grinding machine, the combination of a movable grinding wheel support, a nut rotatably mounted thereon, a non-rotatable screw engaging said nut, a connecting rod connected with said screw, an eccentric for operating said connecting rod, a shaft for operating the eccentric, a power shaft, a clutch between said shafts for connecting them, and means for automatically releasing the clutch.
11. In a grinding machine, the combination of a movable grinding wheel support, an adjusting device connected therewith, a connecting rod connected with said adjusting device, an eccentric for operating said connecting rod, a power shaft, a clutch for connecting said power shaft to operate the eccentric, and means for automatically releasing the clutch.
12. In a grinding machine, the combination of a movable grinding wheel support, a shaft, a second shaft, a clutch for connecting said shafts, means operated by the second shaft for reciprocating said support, a spring normally tending to release said clutch, means for positively locking the clutch in closed position, and means for automatically releasing the clutch and allowing the spring to close it.
13. In a grinding machine, the combination of a grinding wheel support, a shaft, a second shaft, a clutch for connecting said shafts, hand operated means for throwing the sections of said clutch into engagement with each other, means for positively locking the clutch in closed position, resilient means for normally opening the clutch, and means for automatically releasing the locking means comprising a movable member.
14. In a grinding machine, the combination of a grinding wheel support, means for reciprocating said support, a clutch for disconnecting said means from a source of power, manually operated means for closing the sections of said clutch, yielding means normally tending to open the clutch sections, means for automatically and positively locking the clutch in closed position to prevent the opening thereof by said manually operated means, means for releasing the locking means, and movable means mounted to reciprocate with said support for engaging the releasing means and operating it.
15. In a grinding machine, the combination of a grinding wheel support, means for reciprocating said support, a clutch for disconnecting said means from a source of power, manually operated means for closing the sections of said clutch, means normally tending to open the clutch sections, means for automatically locking the clutch in closed position to prevent the opening thereof by said manually operated means, means for releasing the locking means, and movable means mounted to reciprocate with said support for engaging the releasing means at the end of the stroke of said support and permitting the clutch to open.
16. In a grinding machine, the combination of a grinding wheel support, means for reciprocating said support, a clutch for disconnecting said means from a source of power, manually operated means for closing the sections of said clutch, means normally tending to open the clutch sections, and means for automatically and positively locking the clutch in closed position to prevent the opening thereof by said manually operated means.
17. In a grinding machine, the combination of a grinding wheel support, means for reciprocating said support, a clutch for connecting said means with and disconnecting it from a source of power, means for positively locking the clutch and means for automatically unlocking and disconnecting the clutch operable only at the end of the stroke of said support.
18. In a grinding machine, the combination of a grinding wheel support, means for reciprocating said support, a clutch for connecting said means with and disconnecting it from a source of power, and means for automatically disconnecting the clutch operable only at the end of the stroke of said support, said last named means comprising a striker mounted to move with said support, and tiltable thereon into inoperative position.
19. In a grinding machine, the combination of a movable grinding wheel support, means for reciprocating said support, means operable for disconnecting the reciprocating means from a source of power, and a striker mounted to move with the support for engaging the disconnecting means and operating it, and tiltable thereon into inoperative position.
20. In a grinding machine, the combination of a movable grinding wheel support, means for moving said support, adjustable means for disconnecting the moving means from a source of power, and means mounted on said support for engaging the disconnecting means and operating it at the end of the stroke of the support.
21. In a grinding machine, the combination of a movable grinding wheel support, means for moving said support, adjustable means for disconnecting the moving means from a source of power, and means mounted to move with said support for engaging the disconnecting means and operating it at the end of the stroke of the support, said means comprising a pivoted striker adapted to reciprocate in position to engage said disconnecting means when swung to a certain position.
22. In a grinding machine, the combination of a movable grinding wheel support, means for reciprocating said support, means operable for disconnecting the reciprocating means from a source of power, and a striker pivotally mounted on the support for engaging the disconnecting means and operating it.
23. A grinding machine having means for moving a support for the grinding element and automatic stopping device thereon comprising a striker pivotally mounted on the support.
24. A stopping device for the traverse of a grinding wheel consisting of a pivoted striker adapted to be held both in operative and in inoperative position by gravity.
25. A stopping device for the traverse of a grinding wheel comprising a bracket, and a striker pivoted thereon at a point above the bracket and beyond the end thereof, whereby the striker will be held by gravity in substantially upright position by its lower end engaging the end of the bracket, and whereby it will rest by gravity in substantially horizontal position on the bracket when turned in such position.
26. In a grinding machine, the combination of a pair of pillow-blocks, each having bearings thereon for an axle or the like, a right and left-hand screw engaging the two pillow-blocks, stationary means for supporting said screw, a ratchet wheel on said screw, and means for turning said ratchet-wheel to operate the screw and simultaneously adjust the two pillow-blocks.
27. In a grinding machine, the combination of a pair of movable grinding wheel supports, means for simultaneously reciprocating said supports, means for rotating the grinding wheels on both supports, a counter-shaft, and a plurality of means on the counter-shaft for operating both reciprocating means and both rotating means.
28. In a grinding machine, the combination of a plurality of movable grinding wheel supports, means for simultaneously reciprocating said supports, means for rotating the grinding wheels on said supports, means for rotating the work, a counter-shaft, and a plurality of means on the counter-shaft for operating said reciprocating means and rotating means.
29. In a grinding machine, the combination of a movable grinding wheel support, a grinding wheel thereon, means for rotating the work adjacent to said grinding-wheel, a counter-shaft, means on the counter-shaft for operating the work rotating means, said work rotating means comprising a shaft, a gear rotatably mounted on the shaft and having a clutch section thereon, a clutch section slidably operated on the shaft, means for operating the sliding clutch section, a worm on said shaft, a worm-wheel engaging the worm, and a work drive operated by said worm-wheel.
30. In a grinding machine, the combination of a work-drive stand having an open topped bearing, a rotary element supported by said bearing and having ways, an equalizing plate mounted to slide in said ways and provided with ways at an angle to the first named ways, and

a work drive dog mounted to slide in the ways on the equalizing plate, said equalizing plate and work drive dog being adapted to receive said rotary element.

31. In a grinding machine, the combination of a work-drive stand, having an open-topped bearing thereon, a worm-wheel supported by said bearing, means for rotating said worm-wheel, a horse-shoe shaped equalizing plate mounted to slide in ways on said worm-wheel, and a similar shaped work-drive dog mounted to slide in ways

10 at an angle to the first named ways on the equalizing plate.

32. A grinding machine having a work-drive mechanism comprising a rotatable element having ways, an equalizing plate mounted in said ways, said plate having ways at an angle to the first named ways, a work-drive dog mounted

15 on the last named ways, and means on the work-drive dog for engaging an axle or the like and transmitting a motion of rotation thereto from the rotatable element.

33. A grinding machine having a work-drive mechanism comprising a rotatable element having ways, a horse-shoe shaped equalizing plate mounted in said ways, said plate having ways on the opposite side thereof at an angle to the first named ways, a horse-shoe shaped work-drive dog mounted on the last named ways, and adjustable elements

20 on the work-drive dog for engaging an axle or the like and transmitting a motion of rotation thereto from the rotatable element.

34. A floating drive for a grinding machine comprising a horse-shoe shaped equalizing plate and a horse-shoe

shaped work-drive dog slidably connected together, said dog being provided with adjustable means for engaging a 30 shaft or axle passing through the center of the plate and dog.

35. In a grinding machine, the combination of a work-drive stand having an open-topped bearing thereon, a rotatable element supported in said bearing, an equalizing 35 plate movably supported by said element, a work-drive dog on said plate and free to slide with respect thereto, means on the rotatable element for preventing the entire displacement of said dog, adjusting screws carried by said dog for holding the work, a pair of pillow blocks for 40 supporting the work, and means mounted in said work-drive stand and engaging the pillow-blocks for adjusting them.

36. In a grinding machine, the combination of a work-drive stand, a right and left-hand screw mounted thereon, 45 a pair of pillow-blocks having screw-threads for the reception of said screw, means on the pillow-blocks for supporting the work, and a floating drive on the work-drive stand for driving the work.

In testimony whereof I have hereunto set my hand, in 50 the presence of two subscribing witnesses.

CHARLES H. NORTON.

Witnesses:

ALBERT E. FAY,

HENRY H. LEPPER.
